UNITED STATES PATENT OFFICE.

PATRICK J. CLARKE, OF CHICAGO, ILLINOIS, ASSIGNOR OF ONE-HALF TO MATTHEW JAROS, OF CHICAGO, ILLINOIS.

BURGLAR GUARD.

Application filed December 18, 1926. Serial No. 155,755.

This invention relates to a burglar guard.

One of the objects of the present invention is to provide an improved and simplified form of a burglar guard which is particularly adapted for use in stores, banks, express cars and other places where valuables are kept, for the purpose of preventing robberies, and its object is to so overcome the would be robber as to render it impossible for him to carry out his designs or to escape with his booty before he could be disarmed and placed under arrest.

A still further object of the invention is to provide a simple and improved burglar guard which can be economically manufactured and produced at a reasonable cost.

These and other objects are accomplished by providing construction and arrangement of the various parts in the manner hereinabove described and particularly pointed out in the appended claims.

Referring to the drawings,

Figure 1 is a top plan view showing the construction of my improved form of burglar guard;

Figure 2 is a longitudinal cross sectional view of the same;

Figure 3 is a cross sectional view taken on the line 3—3 in Figure 2; and

Figure 4 is a fragmentary side elevational view showing the safety in position to render the device inoperative.

In illustrating one embodiment of my invention I have shown the same as comprising a casing or container 10 which is preferably made of sheet metal and a removable cover 11 which telescopically connects with the casing 10. The casing 10 is provided with side flanges 12 which in turn are provided with a plurality of gas escaping apertures 13. Pivotaly mounted by means of eyes 14 on the top side of the cover 11 is a bail or striker 15. The bail 15 has one end as shown at 16 extending through the eyes 14 as clearly shown in Figure 1, and supports a torsion spring 17 thereon. One end of the spring 17 is provided with a long end as shown at 18 which normally engages the top side of the cover 11. The other end 50 of the spring as shown at 19 is bent outwardly to engage one side of the bail 15. The spring is normally held under a torsion tension to actuate the bail in a counter clockwise direction when looking at the device from the position shown in Figure 2.

Mounted within the casing 10 is a fragile noxious gas container 20 which in the form shown in the drawings is a glass bottle. This glass bottle container 20 is normally held in a prostrate position within the casing 10 and is prevented from displacement within the container by means of a metal bracket 21 which in turn is secured within the casing in any well known manner and substantially embraces the noxious gas container 20. The bottle or container 20 is provided with a stopper 22. Positioned directly above the glass container 20 is a shatter pin 23 which is reciprocally mounted in the cover 11 of the casing. The shatter pin 23 is supported in position by a sleeve 24 secured to the under side of the cover by rivets 25.

The head of the shatter pin is located in the path of the free end of the striking bail 15 so that when the striking bail is released in the manner hereinafter described, the free end thereof will strike the shatter pin 23, and shatter the noxious gas container or bottle 20 and permit the noxious gas within the container to immediately pass out through the apertures 13 in the cover 11 to fill the room and prevent the robber from accomplishing or carrying out his designs. When the trap or burglar

guard is set the bail 15 is swung to a position shown in Figure 2, in which position a latch 26 pivoted to an eye 27 secured to one side of the cover 11 engages the free end as shown at 28 of the bail 15. Connected to the eye 27 is a string or cord 28' which has the other end thereof connected to the wall of the room in which the trap is set.

Mounted intermediate the ends of the string or cord 28' is an extension spring 29 which normally holds the string taut. Connected to the free end of the latch 26 is a second cord or string 30 which has its free end connected as shown at 31 to the first cord or string 28'. Mounted between the ends of the string or cord 30 is a second extension spring 32 which normally holds the string 30 in a relatively taut position. The other end of the casing 10 is connected to another wall of the room in which the trap is set by means of the third string or cord 33 and at eye 34 which in turn is secured to the cover 11 of the casing. When it is desired to place the trap or guard in position the casing may be positioned on one side of the room where it is hidden from view and

attached by means of the string 33 to one side of the room and the string or cord 28 stretched across the room adjacent the floor so that when the would be robber enters the room he will trip on the cord 28 and release the latch 26 from the free end of the bail 15 which in turn causes the bail through the action of the torsion spring 17 to strike, the shatter pin 23 thereby shattering the glass container 20 containing the noxious gas, and permitting the gas to diffuse through the apertures 13 in the room and overcome the would be robber. When it is desired to render the burglar guard inoperative even though the latch 26 is connected to the bail 15 I have provided a safety in the form of curved bail 35 which is pivoted to the eyes 36 secured to the cover 11. This curved bail 35 is adapted to be swung over so as to embrace the shatter pin 23. (see Figure 4) so that if the bail 15 is accidentally released by the latch 26 the free end thereof will not strike the shatter pin 23.

From the above description it will be seen that I have provided a very simple and efficient burglar guard, and one which can be readily set on the floor across the door of the entrance of a store, bank or even a safe so that the same is positioned in the path of the would be burglar. It will be noted that I have shown in the drawings the noxious gas container as comprising a glass bottle with the ordinary stopper. It will of course be understood that various forms of glass containers having noxious gases under pressure may be utilized with a permanent form of seal so that various pressures and different types of noxious gases may be employed and still be within the contemplation of my invention.

While in the above specification I have described one embodiment which my invention may assume in practice it will of course be understood that the same is capable of modification, and that modification may be employed without departing from the spirit and scope of the invention as expressed in the following claims.

What I claim as my invention and desire to secure by Letters Patent is:

1. A burglar guard comprising a casing, a fragile gas container mounted in said casing, a shatter pin mounted in said casing above said container, a spring actuated

striker mounted upon said casing and adapted to strike said shatter pin and means for locking said striker under spring tension. 55

2. A burglar guard comprising a casing, a fragile gas container mounted in said casing, a shatter pin mounted in said casing in position to engage the fragile gas container, striking and tripping means mounted on said casing and operatively related to said shatter pin, and means for rendering said striking means ineffective to strike said shatter pin. 60

3. A burglar guard comprising a casing, a fragile gas container mounted in said casing, a shatter member mounted in said casing adapted to engage the fragile gas container, a striking member mounted on said casing and engageable with said shatter member, a spring normally engaging said striking member and means pivotally mounted on said casing and adapted to embrace said shatter member for rendering said striking member ineffective to strike said shatter member. 70

4. A burglar guard comprising a casing, a fragile gas container mounted in said casing, a cover for said casing having a plurality of gas escaping apertures therein, a reciprocating shatter member mounted in said cover and positioned above said fragile gas container, a striker pivoted to said cover and spring pressed in a direction to strike said shatter member and a latch pivoted to said cover and normally engaging said striker to hold said striker under spring tension. 80

5. A burglar guard comprising a casing, a fragile gas container mounted in said casing, a shatter member mounted in said casing and adapted to engage said fragile gas container, a spring pressed striker mounted on said casing adapted to engage said shatter member, a latch pivoted to said casing and engageable with said striking member and a tripping connection extending from said latch whereby said latch may be disengaged from said striker for permitting said striker to strike said shatter pin and shatter said fragile gas container. 90

In testimony whereof I have signed my name to this specification, on this 14th day 105 of December, A. D. 1926.

PATRICK J. CLARKE.
